UNITED STATES PATENT OFFICE.

HUGO BLIDSOE, OF NEW YORK, N. Y.

PIPE AND CIGAR HOLDER FOR THE PURPOSE OF ELIMINATING THE NICOTINE.

Application filed April 13, 1926. Serial No. 101,618.

This invention relates to improvements in nicotine eliminators and has for its object to provide a construction, which applied to cigar-holders and pipes would enhance 5 the pleasure of smoking by eliminating the dangerous and nauseating substance called nicotine.

Another object of my invention is to provide a cigar or cigarette-holder, and pipe, 10 which constructed along the lines of my invention should permit people with tubercular or pulmonary ailments to enjoy smoking without any stirring effect.

I accomplish this object by constructing 15 a cigar-holder or pipe in such a manner that the mouthpiece of same will be provided with a chamber adapted to receive an absorptive for retaining the nicotine, and which may be changed from time to time as 20 occasion requires.

Said absorptive may consist of plain cotton, or of a sterilized or disinfecting substance.

With the above and other objects in view, 25 this invention consists of the novel features of construction, combination and arrangements of parts, hereinafter fully described, claimed, and illustrated in the accompanying drawings forming parts of this specification, 30 and in which similar characters of reference indicate corresponding parts in all views, and in which Figure 1 is a transverse, longitudinal sectional view of a pipe with my device applied; Figs. 2 and 3 are detail 35 views.

In applying my principle to a pipe I construct a mouthpiece 25, as shown in Fig. 4, in such a manner, that said mouthpiece through an applied pressure by the fingers 40 may be inserted in the lower part of a pipe 26, said lower part, or tube, is provided with a box-chamber, as at 45, having a tapered perforated end portion, said chamber being detachably mounted in such lower tube 26, thereby facilitating the cleaning of same. 45

The mouthpiece when inserted will project a short distance into said chamber, but not deeper than to leave plenty of space for insertion into same of an absorbent substance 50 as previously described.

To further arrest the influence of the nicotine in a pipe I construct the head of same to also embrace my device, which will be appreciated as I proceed with the description. 55

The head 29 comprises three sections 30,

31, 32. The upper one 30 has the usual shape of a pipe head and is integrally connected to the channels 27 and 28. Said head is at its middle portion provided with an edge 60 33 adapted to support a circular disc 34, said disc being provided with apertures 35 to permit the entrance of smoke to the channels.

The disc has at one side a small projection 36 adapted to engage a correspondingly formed recess 37 in the inner wall of the pipe, extending from the edge 33 to the mouth of said pipe, to guide said disc in its up and downward movement, when it is desired to clean the pipe-head. In order 70 to perform such movement for the purpose of cleaning the disc has integrally attached to it at the center of its lower surface, part of an extensible tube 38 adapted to perform a telescopic movement with another tube 75 member 39; when extended said tubes are held in locked position by engagement of an eyelet 40 on 39 with a button 41 on 38.

In the space between the disc 34 and the member 31, I place for the same reasons as 80 before described an absorbent substance 44 which may be inserted by unscrewing the bottom 31 which is threaded upon the member 30.

In order to permit of the afore described 85 cleaning process it will not be necessary to remove the bottom member 31 but merely to unscrew a button 32 threaded in said bottom member, whereby sufficient access is gained to operate said disc and tube members; in order easily to grasp said extensible tube member I provide the same with a small flange 42, which ordinarily rests on the button 32 when the latter is screwed in place.

To secure said pipe in an erect position, 95 when not in use, and thereby prevent any spilling of ashes and soot, I attach to the outside of said pipe-head a collapsible member 43.

It is obvious that changes may be made 100 in the form of construction and arrangement of the several parts, as shown within the scope of the appended claim, without departing from the spirit of the invention, and I do not therefore limit myself to the 105 construction and arrangement shown and described herein.

What I claim as new, and desire to secure by Letters Patent of the United States, is:

A pipe, comprising a mouthpiece adapted 110 to be inserted in a lower member, said member being formed with a seat for a detach-

able chamber having a tube integrally connected thereto, said tube being tapered into a sharp end point and having perforated walls to admit the smoke; the said lower member being provided with two tubes leading into a pipe, the head of said pipe comprising three sections, an upper larger one, having a circular shoulder located intermediate thereof, and adapted to support a disc, provided with apertures, an enlargement on said disc and a corresponding recess in the head of the pipe to permit of an up and downward sliding movement of said disc, an extensible telescopic tube, having its

upper endpiece integrally attached to said disc and means for locking said tube members together when in extended position; a middle section screwed into said upper section and forming a chamber with said disc, said chamber being filled with an absorbent substance; and a bottom section screwed into said middle section and adapted to support a flange on said extensible tube when the latter is in collapsed position.

In witness whereof I have hereunto affixed my signature.

HUGO BLIDSOE.
